(57) **CLAIM**

The ornamental design for a LED luminaire, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of the LED luminaire of the present invention, in which the broken lines depict portions of the luminaire that form no part of the claimed design;

FIG. 2 is a back view thereof, in which the broken lines depict portions of the luminaire that form no part of the claimed design;

FIG. 3 is a top, back, left perspective view thereof, in which the broken lines depict portions of the luminaire that form no part of the claimed design;

FIG. 4 is a top, back, right perspective view thereof, in which the broken lines depict portions of the luminaire that form no part of the claimed design;

FIG. 5 is a left view thereof, in which the broken lines depict portions of the luminaire that form no part of the claimed design;

FIG. 6 is a right view thereof, in which the broken lines depict portions of the luminaire that form no part of the claimed design;

FIG. 7 is a front downward perspective view thereof, in which the broken lines depict portions of the luminaire that form no part of the claimed design; and,

FIG. 8 is a front upward perspective view thereof, in which the broken lines depict portions of the luminaire that form no part of the claimed design.

The broken line areas in the Figures show environmental subject matter and form no part of the claimed design.
